ABSTRACT OF THE DISCLOSURE

A circuit breaker has a movable contact carried by a contact operating member and automatic operating means and manual operating means for effecting movement of the contact operating member from closed to open circuit position. Disengageable means is provided to couple the manual operating means to the contact operating member for normal operation thereof, but the coupling means is disengageable upon operation of the automatic operating means to permit opening movement of the contact operating member independently of the manual operating means. The coupling means includes a resiliently deflectable spiral spring member encircling the contact operating member and seated in cooperating recesses in opposed surfaces of two relatively movable portions of the coupling means. There is also disclosed means for resisting inadvertent operation by acceleration forces.

BACKGROUND OF THE INVENTION

The increasing use of electric power for various purposes has produced a requirement for electric power supply systems of ever increasing capacity and a concurrent requirement for circuit breakers capable of interrupting the high short circuit currents which can occur in such power systems. Moreover, it has been recognized that it is desirable to prevent the short circuit current from attaining a magnitude during interruption which approaches the prospective short circuit current maximum since even the interrupted short circuit current may cause damage to other circuit components. This function is referred to as "current limiting."

As a result, special "current limiting" electric circuit breakers have been developed employing means for separating the breaker contacts by electromagnetic forces with virtually no time lag, upon the occurrence of a high short circuit current. A highly effective electric circuit breaker of this type is disclosed in Patent No. 3,384,846, Heft, issued May 21, 1968 and assigned to the same assignee as the present invention.

As disclosed in the aforementioned Heft patent, it is highly desirable to open the contacts of the circuit breaker, as rapidly as possible, thereby drawing the arc quickly. As further pointed out in this patent, operation of the moveable contact is desirably made independent of movement of the relatively massive elements of the manual-and-conventional-automatic switching mechanism so that the inertia of these systems do not detract from rapid opening. To this end, the Heft device includes a disengageable coupling between the manual-and-conventional-automatic operating mechanism and the contact operating rod which has proven effective.

It is an object of the present invention to provide a current limiting circuit breaker which is capable of rapidly opening the contacts independently of operation of the manual operating mechanism and which may be simply and economically constructed.

It is also an object to provide such a circuit breaker wherein the elements are normally held firmly engaged for manual operation but are readily disengageable upon

2

actuation of automatic operating means functioning in response to current of high magnitude, such as that occurring during a short circuit condition.

Another object is to provide such a circuit breaker which may be readily assembled and disassembled and which is capable of long lived operation and ready variation in the magnitude of current required for automatic operation.

A further object is to provide such a circuit breaker having means for lessening the likelihood of inadvertent operation by acceleration forces.

SUMMARY OF THE INVENTION

It has now been found that the foregoing and related objects can be readily attained in an electric circuit interrupter having a casing containing a stationary contact and a movable contact with a contact operating member carrying the movable contact at one end thereof. Means in the casing mounts the contact operating member for movement of the movable contact between closed and open circuit positions, and automatic operating means connected to the contact carrying member provides for movement thereof from closed to open circuit position upon passage of a short circuit current of predetermined magnitude therethrough. Manual operating means is provided in the casing, and coupling means connects the manual operating means to the contact operating member for movement thereof between closed and open circuit positions.

The coupling means includes a coupling member connected to the manual operating means and disengageable means connecting the coupling member to the contact carrying member. The disengageable connection between the coupling member and the contact carrying member includes a spring member of generally toroidal configuration encircling the contact operating member and being capable of resilient variation in its diameter. The opposed surfaces of the contact carrying member and coupling member have aligned recesses therein each partially receiving the spring member in the normal operative condition of the assembly to provide a connection therebetween for operation of the contact carrying member upon movement of the manual operating means. The recess in one of the cooperating members is of a depth sufficient to completely receive the spring member as a result of sufficient expansion thereof to permit relative movement of the contact carrying member and the coupling member.

In the preferred aspect, the spring member is of the "garter" spring type, i.e., a spring wire coiled in a toroidal configuration. The spring member may be of either the tension type or the compression type so as to be expandable or compressible to effect the desired deflection depending upon the construction and dimensioning of the parts permitted in a given assembly. Accordingly, the member having the grooves or recesses or a depth sufficient to receive the full thickness of the spring may be either the coupling member or the contact carrying member. Various other features and additional elements of construction may be utilized within the present invention for optimum operation as will be pointed out in detail hereinafter.

BRIEF DESCRIPTION OF THE DRAWINGS

FIGURE 1 is a side elevational view of an electric circuit breaker embodying the present invention with portions broken away to reveal internal construction and with the movable contact member shown in the manually operated closed circuit or "on" condition in full line and in the automatically operated "off" condition in phantom line;

FIGURE 2 is a fragmentary side elevational view illustrating the movable elements of the circuit breaker of FIGURE 1 in the manually operated "off" or open circuit condition;

DETAILED DESCRIPTION OF THE ILLUSTRATED EMBODIMENTS

Turning first in detail to FIGURES 1-7, therein illustrated is a circuit breaker having an insulating casing generally designated by the numeral 10 with side walls 12, 14 and a top wall 16. Mounted in the casing by suitable means (not shown) is a pair of spaced stationary contact assemblies generally designated by the numerals 18, 20 and which have opposed contact faces 22, 24 adjacent their inner end and diverging arc runner portions 26, 28. Movable into and away from contact with the contact faces 22, 24 are the contact faces 30, 32 of the generally wedge-shaped movable contact member generally designated by the numeral 34 carried on the end of the elongated contact operating rod 36. Received between the inner end portions 38, 40 of the stationary contact assemblies 18, 20 is a generally cup-shaped insulating member 42 which provides a pressure chamber 44 about the region of movement of the movable contact member 34 and which has a close fitting aperture 46 in the end wall thereof in which the contact operating rod 36 is slidable.

A line terminal 48 on the casing 10 supplies current to the conductive strap 50 which is electrically connected to the stationary contact assembly 18 by the conductor 52. A blowout coil is provided by the winding of the conductor 52 about the metal core 53 to move the arc out along the arc runner portions 26, 28 as pointed out in the aforementioned Heft patent. The conductor 56 connected to the stationary contact assembly 20 is likewise wound about a metal core 54 to provide a blowout coil cooperating with the arc runner portion 28. At its opposite end, the conductor 56 is attached to the terminal 58 of the solenoid 60 which in turn is connected to the strap 62 of the load terminal 64 by the conductor 66.

As a result, the current path through the circuit breaker is from the line terminal 48 to the strap 50 and thence through the conductor 52 to the stationary contact assembly 18. When the movable contact member 34 is in closed circuit position, the current flows from the contact face 22 to the contact face 30 of the movable contact member 34 and thence to the contact face 24. Since the face 24 is connected by the conductor 56 to the solenoid 60, the current flows therebetween and thence through the line 62 to the strap 66 of the load terminal.

In accordance with conventional practice, the breaker includes manual operating means for moving the contact operating rod 36 to and from closed circuit position with respect to the contact faces 22, 24, which means includes a manually engageable handle member 68 projecting out-

wardly through an aperture 70 in the top wall 16 of the casing 10. The generally inverted U-shaped handle support member 72 within the casing 10 has slots 74 in the free ends of its legs which pivotally seat on the fixed pivot pins 76 on the support brackets 80, 82 of the casing 10 so as to be pivotal between the positions shown in FIGURES 1 and 2 of the drawings. A pair of offset connecting links 78 are pivoted at their upper end by the pins 76 and have elongated slots 84 at their lower ends which receive pivot pins 86 on the sides of the coupling member generally designated by the numeral 88. A pair of operating springs 90 are connected at their upper ends to pins on the upper portion of the handle support member 72 and at their lower ends to the connecting links 78 to provide a toggle action.

When the parts are in the "on" condition shown in full line in FIGURE 1, the line of action of the operating springs 90 lies to the left of the pivot pins 76 as viewed therein or to the side of the pins 76 spaced towards the contact assemblies 18, 20. This biases the connecting links 78 clockwise about the pivot pins 76 and urges the coupling member 88 and thereby the contact operating rod 36 and movable contact member 34 into firm electrical contact with the stationary contact faces 22, 24. When the handle member 68 is moved to the "off" position shown in FIGURE 2, the line of action of the springs 90 is to the right of the pivot pins 76 as viewed therein or to the side of the pins 76 spaced away from the contact assemblies 18, 20. This biases the operating links 78 counterclockwise about the pivot pins 76 and urges the coupling member 88 and thereby the contact operating rod 36 and movable contact member 34 away from electrical contact with the stationary contact faces 22, 24.

As best seen in FIGURES 1 and 2, the contact operating rod 36 carries a solenoid plunger 96 at its end which is slidably received in the tubular sleeve 98 fixedly mounted in the casing 10. A limited amount of sliding movement of the solenoid plunger 96 on the operating rod 36 is provided by the mounting pin 92 which rides in slots 94 of the tubular operating rod 36 which contains a spring (not shown) normally biasing the pin 92 and thereby the plunger 96 beyond the end of the rod 36. On passage of current of a predetermined magnitude through the solenoid 60, the magnetic force of the solenoid and the rapidity of action are sufficient to disengage the releasable connection between the coupling member 88 and the contact operating rod 36 and draw the operating rod 36 away from the contact assemblies 18, 20 to open the contact rapidly. The solenoid plunger 96 strikes against the resilient stop cushion 100 of neoprene or the like which protects the field piece 102 of the solenoid 60. In addition, the rod 36 can continue to move rearwardly relative to the plunger 96 by reason of the pin and slot connection against the action of the spring to provide for some override and damping action.

Similar provision for shock absorption upon closing of the contacts and a lost motion connection upon opening of the contacts is provided by the mounting pin 104 on the plunger portion 106 of the movable contact member 34 which rides in slots 108 in the contact operating rod 36. A spring (not shown) in the tubular operating rod 36 biases the plunger portion 106 outwardly of the rod 36 so that upon closing of the contacts some override of the operating rod 36 and damping action is provided. Upon opening movement of the rod 36, the connection enables some lost motion between the rod 36 and contact member 34 before the contacts are actually opened.

Turning now in detail to the embodiment of disengageable connection between the coupling member 88 and the operating rod 36, this is best seen in FIGURES 4-7 of the attached drawings. The coupling member 38 is of generally cylindrical or toroidal cross section with a pair 75 of radial bosses 110 (see FIG. 7) having the pins 86

thereon and also has a bore 112 extending therethrough with a reduced diameter portion at the end adjacent the contact assemblies 18, 20 providing a circumferential shoulder 113. An annular groove 114 extends about the inner circumference of the coupling member 88 adjacent the end closest to the solenoid plunger 96 and is dimensioned to provide a depth sufficient to receive the full thickness of the coiled, annular "garter" spring member 116 which normally only partially seats therein.

The operating rod 36 has fixed thereon by the pin 118 a tubular sleeve generally designated by the numeral 120. A circumferential groove 122 in the member 120 is aligned with the groove 114 of the coupling member 88 in the normal operating position as shown in FIGURE 4 and is of relatively shallow depth so as to receive only a portion of the thickness of the spring member 116. In this manner, the spring member 116 provides interengagement between the coupling member 88 and member 120. The member 120 has a reduced diameter end portion adjacent the contact assemblies 18, 20 providing a circumferential shoulder 124 between it and the major diameter portion, and this reduced end portion seats in the reduced diameter end portion of the bore 112 with the shoulders 113, 124 in abutting contact in the normal operative position of the members.

In normal operation of the circuit breaker, the garter spring seats partially within the grooves 114, 122 of the coupling member 88 and the member 120 of the contact operating rod 36 since the groove 122 is of lesser depth than the thickness of the spring 116. Upon rapid actuation by the passage of a short circuit current through the solenoid 60, the force of the operating rod 36 causes the side wall of the groove 122 to press against the spring 116 and expand it in diameter until it passes completely into the groove 114 of the coupling member 88. This allows the operating rod 36 to move independently of the coupling member 88 and the remainder of the operating mechanism and thus be free of the inertia thereof. As the contact operating rod 36 moves toward the cushion 100, the spring 116 rides along the surface of the sleeve 120 until it drops onto the reduced portion and the shoulder 124 provides an abutment to prevent the contact rod 36 from bouncing back and reclosing the contacts.

The radius of the coils of the garter spring member 116 and its diameter and strength are selected with respect to the grooves or recesses 114, 122 of the cooperating members 88, 120 so that the force exerted thereby will normally resist relative movement between the member 88 and the member 120. Operation of the handle member 68 thus will produce movement of the operating rod 36 between open and closed circuit positions. Although the solenoid 60 is exerting a magnetic force on the solenoid plunger 96 at all times during current flow through the breaker, it is generally a relatively low force. In an instance of a short circuit current of predetermined magnitude, however, the force of the solenoid acting on the rod 36 cams the spring 116 outwardly from the recess 122 of the sleeve 120 as it draws the rod 36 axially towards the solenoid 60. Although the force of the solenoid 60 under the predetermined conditions for automatic tripping is much greater than that of the operating springs 90, the manual operating mechanism is not moved to the open circuit position when this occurs largely because of the inertia of these parts. Instead, the operating rod 36, together with the member 120, the solenoid plunger 96 and the movable contact member 34 move without being impeded by the inertia of the elements of the manually operable mechanism although the coupling member 88 remains in substantially the same position. Although the spring 116 is deflected and expands sufficiently to allow sliding within it of the outer surface of the sleeve 120, it quickly closes around the forward end of the member 120 beyond the shoulder 124 to pre-

vent the movable contact assembly from moving back or rebounding toward closed circuit position.

Following automatic opening, the mechanism may be reset to permit reclosing simply by moving the operating handle member 68 to its normal off condition, thereby returning the garter spring member 116 into engagement in the groove 122 of the member 120. The circuit breaker may then be reclosed by returning the handle member 68 to its "on" position as shown in FIGURE 1.

Turning now to FIGURES 8-10, therein illustrated is an embodiment of the present invention particularly suitable for use in vehicles or military applications where inadvertent operation as a result of environmental acceleration is to be avoided. In this embodiment, the general construction is the same as in the embodiment of FIGURES 1-7 with the same members being employed for unmodified elements. The operating rod 36 again has a member 120 fixed thereto by the pin 118 and has a configuration similar to that of FIGURES 4-6 with a groove 122 therein partially seating a garter spring 216 of the tension type. The coupling member generally designated by the numeral 288 is generally similar in construction to that of the prior embodiment except that a depending boss 282 is provided thereon and slots 280 are milled in the sides thereof normally to the longitudinal axis of the rod 36 and in alignment with the location of the groove 214 therein.

In this embodiment, a flat strip type metal spring of generally U-shaped configuration and generally designated by the numeral 300 has its base or web portion 302 fastened by the boss 282 of the coupling member 288 by the threaded member 304. The elongated legs 306, 308 of the spring 300 are deformed inwardly intermediate their length to provide convexly arcuate portions 310, 312 bearing against the circumference of the garter spring 216 exposed by the slots 280 in the sides of the coupling member 280. A counterweight 314 is carried by a web or weight mounting spring 316 of generally V-shaped configuration extending between the legs 306, 308 of the sheet metal spring 300 adjacent the upper ends thereof. The Y-type connection enables variation in the spacing of the ends of the branches of the Y and thereby the spacing between the upper ends of the legs 306, 308.

As shown in FIGURE 9, the counterweight 314 and V-shaped web spring 316 are disposed towards the solenoid and away from the contacts. In the event of forces of acceleration normally tending to disengage the coupling by reason of the relative action of inertia upon the several members, the accelerating forces act on the counterweight 314 to produce deflection of the web spring 316 as shown in phantom line in FIGURE 10 to pull the upper ends of the legs 306, 308 together. This in turn causes the arcuate portions 310, 312 to bear against the garter spring 216 with greater pressure to resist the tendency for expansion of the garter spring 216 and uncoupling of the connection.

By proper selection of the mass of the counterweight 314 and selection of stock for and configuration of the springs 300 and 316, the forces of acceleration acting on the counterweight 314 can substantially equal those produced by acceleration acting on the remaining members and tending to produce uncoupling. Thus, proper operation of the disengageable connection will occur even during periods of acceleration or deceleration. Moreover, the biasing pressure exerted by the spring legs 306, 308 can be utilized to determine the force required to be exerted by the solenoid to effect disengagement of the garter spring 216 not only at times of acceleration but also during periods of rest or constant speed.

The counterbalance embodiment of FIGURES 8-10 is especially advantageous for vehicles or for military applications where the circuit interrupter is mounted on an element subject to forces of acceleration such as a gun platform or carriage. Assuming that the breaker were rated for normal operation at 100 amperes with a trip

rating of 500 amperes and assuming a current of 450 amperes were flowing therethrough, it can be seen that the force being exerted by the solenoid tending to disengage the coupling is almost sufficient to effect tripping. If acceleration now occurs, it is likely that the inertia acting on the elements of the normal operating mechanism will now cooperate with the solenoid force in overcoming the force of the spring member and produce spurious tripping of the breaker which could be highly disadvantageous from the standpoint of operation of a vehicle or of military equipment. By providing the counterbalance assembly, the same acceleration forces act to increase the pressure required to disengage the spring member so that tripping of the breaker is left essentially solely to the action of the solenoid and thereby to calibrated action.

Although both of the illustrated embodiments utilize tension springs, it will be appreciated that compression springs may also be utilized in the present invention by reversing the arrangement of grooves or recesses in the cooperating members so that the inner member is of a depth to receive sufficient of the thickness of the spring member upon compression thereof to release the coupling member. Moreover, it should also be appreciated that two or more spring members may be seated in cooperating recesses in the coupling and contact carrying members to permit variation in the solenoid force required to effect disengagement or variation in the nature and dimensioning of the several elements.

Other types of spring members may be utilized such as expansible bands and synthetic and natural elastomers may also be employed. However, coiled metallic garter springs of the type illustrated are preferred for the present application since they are readily adaptable to close adjustment in spring power and tend to provide predictable operation over a wide range of temperatures. Moreover, the arcuate surface of the coil affords some camming action to facilitate uncoupling and minimizes surface friction as the spring member and released member slide relative to each other.

The recesses for receiving the spring member may assume a variety of cross-sections so long as they permit the spring member to move relative thereto. They may be annular grooves extending about the entire periphery of the members as illustrated in the embodiment of FIGURES 1-7 or extend only partially about the member as illustrated with respect to the coupling member of the embodiment of FIGURES 8-10. In addition, a plurality of pairs of ribs spaced about the periphery of the member may provide suitable spaces or recesses therebetween. The recess or groove in the one member is preferably of a depth to receive the full thickness of the spring member when it is deflected, thereby permitting snug fitting of the coupling member and the contact operating rod or its sleeve member 120 to prevent any axial misalignment. However, if some radial clearance is provided between the two coupled members, then the depth of the groove or recess required to accept the spring member for uncoupling is reduced accordingly.

By utilizing a hollow or tubular contact operating rod and lightweight material for the sleeve member, the inertia of the uncoupled subassembly may be minimized to enhance the rapidity with which the contacts may be opened. In the illustrated embodiment, a shoulder is provided to cooperate with the spring member in the automatically operated position to hold the contact operating rod against reclosing or bouncing back. In place of such a shoulder, a second groove or recess can be provided in the released member to receive the spring member in the open contact position.

Similarly, the counterbalance embodiment is also variable in the nature of its components. If a compression spring is employed for the disengageable coupling, then the counterbalance mechanism may employ a pair of spring members spaced axially to opposite sides of the legs of the spring member with relatively rigid connectors

extending therebetween inwardly of the spring member. In such a version, the V-shaped spring and counterweight should be reversed in orientation with respect to their disposition relative to the contacts from the arrangement shown in the embodiment of FIGURES 8-10. Thus the force of acceleration will cause the effective length of the spring to expand and deflect the arms of the spring outwardly which, in turn, causes an increase in force necessary to compress the spring sufficiently to produce de-

coupling.

Other types of manual operating mechanisms may also be employed in accordance with the present invention including the type having a releasable "cradle" or other means for achieving automatic opening of the movable contact without disengagement of the coupling means. In the invention in this form, therefore, as in the aforesaid patent 3,384,846, there would be manually operable means for opening and closing the contacts, first automatic means for opening the contacts by automatic operation of the manually operable mechanism, and second automatic opening means (such as solenoid 60) for opening the contacts independently of the manual operating means.

Although the present invention may be utilized in any circuit interrupter where extremely rapid opening of the contacts is desired upon passage of a high short circuit current therethrough, it is particularly advantageously employed in current limiting type circuit breakers, where almost instantaneous opening of the contacts is desired.

Thus it can be seen that the present invention provides a novel circuit breaker capable of rapidly opening the contacts independently of operation of the manual operating mechanism. The devices may be simple and relatively economically constructed and are readily adapted to variation in the magnitude of the short circuit current required to effect uncoupling such as by adjusting the number of turns of the solenoid or by adjusting the force of the "garter" spring. By use of the counterbalance principle herein disclosed, the present invention is highly effective to ensure precise operation even in applications where the interrupter is subjected to accelerational forces when handling a current approaching the trip value.

What I claim as new and desire to secure by Letters Patent of the United States is:

1. In an electric circuit interrupter, the combination comprising:
  - (a) a casing;
  - (b) a stationary contact in said casing;
  - (c) a movable contact in said casing;
  - (d) a contact operating member carrying said movable contact at one end thereof;
  - (e) means mounting said contact operating member in said casing for movement of said movable contact between closed and opened positions;
  - (f) automatic operating means connected to said contact operating member for moving said contact operating member from closed to open circuit position upon passage of a current of predetermined magnitude therethrough;
  - (g) manual operating means; and
  - (h) means coupling said manual operating means to said contact operating member for moving said contact operating member between closed and open circuit positions, said coupling means including a coupling member about said contact operating member, means engaging said coupling member and said manual operating means for translation of movement thereby, and a disengageable connection between said coupling member and contact operating member including a spring member of generally toroidal configuration encircling said contact operating member and being capable of resilient variation in its diameter, the opposed surfaces of said coupling member and said contact operating member having aligned recesses therein each partially receiving said spring

member in the normal operative position thereof to provide a connection therebetween for operation of said contact operating member upon movement of said manual operating means, one of said members having its recess of a depth to completely receive said spring member upon deflection of said spring member to permit relative movement between said coupling member and said contact operating member.

2. The circuit interrupter of claim 1 wherein said spring member is a coiled spring of toroidal configuration.

3. The circuit interrupter of claim 1 wherein said recesses in said coupling and contact operating members are provided by generally annular grooves in the surface thereof.

4. The circuit interrupter of claim 1 wherein said spring member is a compression spring and wherein said contact operating member has a recess of a depth to receive the thickness of the annular spring member normally biased into the recess of said coupling member.

5. The circuit interrupter of claim 1 wherein said spring is a tension spring and wherein said coupling member has a recess of a depth sufficient to receive the thickness of the annular spring member normally biased into the recess of the contact operating member.

6. The circuit interrupter of claim 1 wherein said other member is shaped to provide means for engagement with said toroidal spring member in the open circuit position for holding said contact operating member in open circuit position.

7. The circuit interrupter of claim 6 wherein said means is a generally annular shoulder on said other member.

8. The circuit interrupter of claim 1 wherein said automatic operating means includes a solenoid in said casing and a solenoid plunger on said contact operating member attractable by said solenoid upon passage of a current of sufficient magnitude therethrough to overcome the force of said spring member.

9. The circuit interrupter of claim 1 wherein said coupling means includes counterbalancing means subject to accelerational forces to increase the pressure required to be exerted upon said spring member for deflection outwardly from the recess of said other member to disengage the connection between said coupling member and said contact operating member.

10. The circuit interrupter of claim 9 wherein said counterbalancing means includes auxiliary spring means carried by said coupling member and having elongated leg portions extending normally to the axis of said contact operating member, a generally V-shaped web spring extending between said legs adjacent the upper end thereof

and a weight on said web spring to produce deflection of said web spring and thereby the legs of said auxiliary spring means, said deflection of said auxiliary spring means acting to increase the pressure required to deflect said annular spring outwardly from the recess of said other member.

11. The circuit interrupter of claim 10 wherein said toroidal spring member is a tension spring and said one member having said recess of a depth to receive the thickness of the spring member is said coupling member and wherein said coupling member has apertures communicating with the recess therein and receiving the leg portions of said auxiliary spring means intermediate their length, said leg portions of said auxiliary spring means bearing against the outer periphery of said toroidal spring member during acceleration as a result of contraction of the spacing between the ends thereof through action of accelerational forces on said weight carried by the web spring.

12. The circuit interrupter of claim 11 wherein said leg portions of said auxiliary spring means have convexly arcuate portions intermediate their length generally conforming to the periphery of said annular spring member.

13. The circuit interrupter of claim 10 wherein said annular spring member is a compression spring and wherein said one member having a recess of a depth to receive the thickness of the annular spring member is said contact operating member and wherein said auxiliary spring means comprises a pair of spring elements each having leg portions to opposite sides of said coupling member and relatively rigid elements extending therebetween axially of said contact operating member and inwardly of said annular spring member, said weight producing expansion in spacing between the ends of said leg portions of said spring elements and thereby an outward pressure acting against said annular spring member during accelerational force.
